COOLING TOWER

Allan Shakespeare Richardson, Butte, Mont.

Application March 12, 1938, Serial No. 195,536

5 Claims. (Cl. 261—112)

This invention relates to cooling towers, particularly of the forced draft type for cooling liquids, and aims to provide certain new and useful improvements in apparatus of this character.

5 In liquid cooling towers of the forced draft type it is customary to permit the liquid to fall in drops from a distributing system at the top of the tower. Passage of the liquid through the tower is retarded by numerous filling pieces of 10 various shapes which catch the drops of liquid from above, and, after the liquid has flowed downward over the surfaces of these filling pieces, it falls in drops onto similar filling pieces below. Such towers may be operated more or 15 less satisfactorily at gas velocities up to about 500 feet per minute, but at higher gas velocities the efficiency of heat transference decreases and liquid is caught by the gaseous draft and blown out of the tower. The efficiency of such towers depends to a large extent upon the falling liquid being divided into small drops, and the smaller drops are more readily blown out of the tower.

The cooling tower of the invention is adapted to secure a high ratio of contact between liquid and gas resulting in a high efficiency of heat transference. This is accomplished, in part, by the provision of a large number of closely-spaced corrugated metal sheets, preferably of special configuration, down which the liquid to be cooled flows in thin films countercurrently with the rising draft of cooling gas. The corrugated sheets have substantially identically but reversely curved surfaces forming ridges and furrows, the reverses in the curvature of the curved surfaces occurring closely adjacent the peaks of the ridges and the depths of the furrows and are spaced from the mid-point therebetween. The ratio of depth of corrugation to pitch of the corrugated sheets is relatively high, preferably about 1 to 3. Preferably, the specially-shaped sheets are of uniform pitch with respect to each pair of reverse curves, with about two-thirds of each curve of uniform curvature and radius. The close spacing of the sheets and their special configuration provide narrow and sinuous channels through which the gaseous cooling medium flows, under forced draft, in a turbulent manner, thereby exercising a scouring-like action that breaks up stagnant liquid films and promotes the rate of heat transference. The liquid to be cooled is delivered separately to each surface of each sheet near but at least several situations below the tops thereof, and preferably at a point below a 55 valley or furrow but slightly above the adjacent

peak or ridge of the sinuous surface of each sheet, in such a manner as not to be caught by the gaseous draft and carried out of the tower. In this manner liquid may be delivered to the sheets during passage of gas at high velocity through the tower without substantial loss of unevaporated liquid by blow-over. Such high velocity of gas passing through the tower may be of the order of at least about 1000 feet per minute.

The foregoing and other novel features of the invention will be better understood from the following description taken in connection with the accompanying drawing, in which

Fig. 1 is a sectional elevation of a cooling tower embodying the invention.

Fig. 2 is an enlarged sectional view through the assembly of reverse curve sheets, and

Fig. 3 is a further enlarged sectional view illustrating the special configuration of the sheets.

The tower or chimney illustrated in the drawing comprises a lower portion 5 of concrete, or the like, and a superimposed upper portion 6 of steel, or the like, both rectangular in section. It will of course be understood that the tower may be built of other materials and may be of any appropriate dimensions. The tower has a lateral opening 7 near its bottom for the introduction of the gaseous cooling medium, and a sump 8 at its base for the collection of the cooled liquid. Liquid is withdrawn from the sump through a discharge pipe 9.

Suspended within the tower is the assembly of closely spaced metal sheets 10 of the preferred special configuration. These sheets are in the form of continuous reverse curves, best shown in Fig. 3 of the drawing. The pitch (a—b) of each pair of reverse curves is uniform and the two reverse curves (a—c and c—b) of each pair are of the same form. For approximately two-thirds of its length (a—d and c—e) each curve is the arc of a circle, and the remainder of the length (d—c and e—b) of each curve is of varying radii. The space between the assembled sheets is approximately the depth of the furrow or corrugation (o—c, Fig. 3).

The vertical edges or ends of each strip 10 are secured to flat strips 11, as for example by soldering or welding the strip to the peaks or ridges on one side of the sheet (Fig. 2). The upper ends of the strips 11 are angularly bent outwardly (12) and rest on brackets 13 secured to opposite sides of the upper portion 6 of the tower. The strips 11 may if desired serve as spacing members for the sheets. The closely-spaced sheets extend

vertically from near the gas inlet 7 to near the top of the tower and provide a multiplicity of narrow sinuous channels for the draft of cooling gas. While the horizontal distance between the sheets is uniform, the distance between the sheets perpendicular or normal to the direction of gas flow is not uniform, but repeatedly contracts and expands. Thus, for each pitch-distance, the area of the channel between the sheets perpendicular to the direction of air flow twice contracts and then expands, thereby providing a succession of Venturi-like passages for the gas flow.

A tank or reservoir 14 is mounted on top of the tower for holding the liquid to be cooled. Pipes 15 and 16 deliver the liquid to a pair of upper headers 17 and a pair of lower headers 18, respectively, the two headers of each pair being on opposite sides of the tower. Liquid distributing tubes 19 and 20 are connected between the pairs of upper and lower headers 17 and 18, respectively. The liquid distributing tubes (within the assembly of sheets) are perforated to deliver the liquid to be cooled onto the surfaces of the sheets 10. The tubes are positioned above the peak of the curve of the surface of the sheet to which it delivers liquid so as to be out of the gas stream. The upper two sets of tubes 19 deliver liquid to the opposite surfaces of the sheets below the tops thereof, preferably two or three corrugations below the tops, so that such liquid as is caught by the gaseous draft before it reaches the surface of the sheet is blown against the sheet at a higher elevation by reversals in the direction of gas flow because of its greater momentum due to its greater density. The liquid then adheres to the sheets and flows downwardly over the surface thereof by gravity. The lower two sets of tubes 20 similarly deliver liquid to the opposite surfaces of the sheets at an appropriate distance below the upper tubes.

The cooling tower of the invention is particularly applicable for cooling water or brine in connection with air-conditioning equipment. Air is the most available gas for cooling. By way of example, the operation of the tower will be described as applied to cooling water by a forced draft of air.

The water (or brine) to be cooled is delivered from the storage tank 14 to the tubes 19 and 20 so that uniform films of water cover both sides of the sheets 10 and flow by gravity countercurrent to the air flow. The liquid film is held to the metal surfaces by surface tension and practically no liquid is carried from the tower by the cooling air. The special configuration of the narrow channels between the sheets causes a considerable turbulence in the air flow which eliminates all so-called channeling effect with its consequent dead air films. The cooling air is blown into the tower by an appropriate fan or blower (not shown) through the opening 7 near its base, and is uniformly distributed to the channels between the sheets by deflecting plates 21. The top of the tower is open for the free discharge of the air. The cooled liquid collects in the sump 8, from which it may be withdrawn as desired through the outlet 9.

The considerations affecting pitch, depth of corrugation, and curvature of corrugation of the sheets 10 of the cooling tower of the invention are briefly as follows:

There is a certain minimum quantity of liquid per minute per horizontal linear foot of sheet surface that is necessary to maintain a uniformly wetted surface, or continuous downwardly

moving film of water. This may vary for different materials used in fabricating the sheets and for different liquids. With galvanized iron sheets in a tower for cooling water or brine, this quantity is approximately 0.15 gallons per minute per horizontal foot of surface, or double that quantity per horizontal foot of sheet since both sides of the sheet are utilized.

Assuming that a given quantity of water is to be cooled through a definite temperature range, and to within a definite temperature difference between it and the air entering and leaving the tower, the quantity of air required must be sufficient to satisfy the heat balance. Transference of heat from water to air increases with increase in the velocity of air motion, and in an approximately straight line relationship as far as can be determined experimentally. However, the resistance to air flow varies as the square of the velocity and hence it follows that there is an economic limit below which it is not possible to decrease the space between the sheets. Nevertheless, the space between the sheets should be of insufficient width to permit a straight line flow therethrough of any appreciable volume of gas.

I have determined that the transference of heat is increased by increasing the number of corrugations per foot of vertical distance, and by increasing the ratio of depth of corrugation to pitch. In this case also, the resistance to air flow is increased by increasing the number of corrugations and by increasing the ratio of depth of corrugation to pitch.

With other conditions constant, efficiency commences to decrease when the sheets are separated beyond the tangent position, and the most efficient arrangement is based upon the best balance of all of the foregoing factors. Obviously, the proportions of corrugations and spacing of sheets may vary widely with different requirements. In a water cooling tower utilizing air as the gaseous cooling medium, the ratio of depth of corrugation to pitch may advantageously be about 1 to 3 and the space between the sheets may be approximately the depth of corrugation. I have obtained very satisfactory results, in a water cooling tower, with galvanized metal sheets having a depth of corrugation of 1½ inches and a pitch of 4½ inches, the arc section (a—d) of the curve having a radius of about 1½ inches for approximately one third (1½ inches) of the pitch. In a water cooling tower with such specially-shaped sheets spaced at about 1¾ inch centers the coefficient of heat transference at an air velocity of about 650 feet per minute is approximately twice as high as with ordinary corrugated sheets of the same pitch and depth of corrugation. In the ordinary corrugated sheet the adjoining reverse curves are symmetrical about a line normal to their junction at the peak of each corrugation. At an air velocity of about 1000 feet per minute the coefficient of heat transference of the specially-shaped sheets of the invention is about 60% higher than with ordinary corrugated sheets.

The improvement in performance of the specially-shaped sheets of the invention is due in part to the fact that two-thirds of the surface of the sheet is available for impingement of the air against the water film as compared with one-half in the case of the ordinary corrugated sheet. However, the actual improvement in performance is considerably greater than the ratio of surfaces exposed to impingement. This, I believe, is due

to turbulence in the air flow induced by the fact that although the horizontal distance between the sheets is constant, the area normal or perpendicular to the lines of air flow is not constant.

5 In other words, there are alternate restrictions and enlargements of the area normal to the lines of air flow, thus imparting to the air flow repeated Venturi-like effects.

In a cooling tower of the invention approximately 40 feet in height, utilizing the specially-shaped sheets of about the dimensions hereinbefore recited and about 29 feet long, I have cooled water from about 75° F. to 50° F. with air entering at a wet bulb temperature of 49° F. In other words, the water was cooled to within 1° F. of the wet bulb temperature of the air entering the tower. At the same time the temperature of the air leaving the tower was up to within 7° F. of the water entering the tower, that is a wet bulb temperature of 68° F. Such a performance would be practically impossible with the heretofore known types of forced draft cooling towers. The estimated height of a conventional cooling tower of the prior art to cool water down to within 4° F. of the wet bulb temperature of the air entering the tower, with a temperature difference of about 7° F. between the air leaving the tower and the water entering the tower, is approximately 200 feet.

30 I claim:

1. In a cooling tower, a series of closely-spaced sinuous sheets operatively positioned within the tower with the spaces between the sheets in any horizontal plane substantially uniform in shape and size and of insufficient width to permit a straight line flow therethrough of any appreciable volume of gas, means for inducing an upward current of gas through the spaces between said sheets, and means for delivering a liquid separately to each surface of each sheet near but at least several sinuations below the upper end thereof, whereby liquid may be delivered to said sheets during passage of gas at high velocity through the tower without substantial loss of unevaporated liquid by blow-over.

2. In a cooling tower, a series of closely-spaced sinuous sheets having successive substantially identical but reversely curved surfaces forming ridges and furrows, the reverses in the curvature of said curved surfaces occurring closely adjacent the peaks of said ridges and the depths of said furrows and being spaced from the mid-point therebetween, said sheets being operatively positioned within the tower to provide a plurality of generally upright and relatively narrow sinuous channels for the flow of gas, the area of said channels perpendicular to the direction of gas flow repeatedly contracting and expanding, means for inducing an upward current of gas through said channels, and means for delivering a liquid to the surfaces of said sheets.

3. In a cooling tower, a series of closely-spaced sinuous sheets operatively positioned within the

tower and providing a plurality of generally upright and relatively narrow sinuous channels for the flow of gas, means for inducing an upward current of gas at high velocity of the order of at least about 1000 feet per minute through said channels, and means for delivering a liquid separately to each surface of each sheet near but at least several sinuations below the upper end thereof and at a point below a valley but slightly above the adjacent peak of the sinuous surface to which the liquid is delivered, whereby liquid may be delivered to said sheets during passage of gas at high velocity through the tower without substantial loss of unevaporated liquid by blow-over.

4. In a cooling tower, a series of closely-spaced sinuous sheets operatively positioned within the tower to provide a plurality of generally upright and relatively narrow sinuous channels for the flow of gas, said sheets being in the form of continuous pairs of substantially identical but reverse curves forming ridges and furrows, the reverses of said curves occurring closely adjacent the peaks of said ridges and the depths of said furrows and being spaced from the mid-point therebetween, the depth of the furrow of each curve being approximately one-third of the pitch of a pair of reverse curves and the spacing of the sheets being such that said channels are of insufficient width to permit a straight line flow therethrough of any appreciable volume of gas, means for inducing an upward current of gas through said channels, and means for causing films of liquid to flow by gravity over the surfaces of said sheets.

5. In a liquid cooling tower, a series of closely-spaced sinuous sheets operatively positioned within the tower to provide a plurality of generally upright and relatively narrow sinuous channels for the flow of cooling gas, said sheets being in the form of continuous pairs of reverse curves forming ridges and furrows, the reverses of said curves occurring closely adjacent the peaks of said ridges and the depths of said furrows and being spaced from the mid-point therebetween, the depth of the furrow of each curve approximately one-third the pitch of a pair of reverse curves and approximately two-thirds of each curve being the arc of a circle, the horizontal width of said channels being substantially uniform and approximately equal to the aforesaid depth of furrow and the width of said channels perpendicular to the direction of gas flow alternately decreasing and increasing throughout the length thereof, means for inducing an upward current of cooling gas through said channels, and separate delivery means for delivering the liquid to be cooled separately to each surface of each sheet near but at least several sinuations below the upper end thereof and at a point slightly above the peak of the sinuous surface to which the liquid is delivered.
